United States Patent Office

Des. 204,603
Patented May 3, 1966

204,603

PUBLIC CONVENIENCE BUILDING

Frank P. Maltese, 461 Otis Road, North Brunswick, N.J.

Filed June 5, 1964, Ser. No. 80,321

Term of patent 14 years

(Cl. D13—1)

FIG. 1

FIG. 2

FIG. 3

FIG. 4

FIG. 5

FIG. 6

FIG. 7

FIGURE 1 is a front perspective view of a new public convenience building embodying my design;

FIGURE 2 is a rear perspective view;

FIGURE 3 is a front elevational view;

FIGURE 4 is a first end elevational view;

FIGURE 5 is a second end elevational view;

FIGURE 6 is a rear elevational view; and

FIGURE 7 is a cross-sectional view taken along line 7—7 of FIGURE 3.

I claim:

The ornamental design for a public convenience building, as shown.
